[57] CLAIM

The ornamental design for a attachment bracket for a pivotal tool handle, as shown and described.

DESCRIPTION

FIG. 1 is a top, front and left side perspective view of a attachment bracket for a pivotal tool handle showing my new design;

FIG. 2 is a top plan view thereof;

FIG. 3 is a bottom plan view thereof;

FIG. 4 is a front elevational view thereof with the rear elevational view being a mirror image thereof;

FIG. 5 is a right side elevational view thereof, taken in the direction of the arrows A—A in FIG. 4; and,
FIG. 6 is a left side elevation view thereof.

The tool head and handle shown in broken lines in the drawings is for illustrative purposes only and forms no part of the claimed design.

FIG. 1

FIG. 2

FIG.3

FIG. 4

FIG. 5

FIG. 6
